UNITED STATES PATENT OFFICE.

ARBA IRA CARNINE, OF NORTH MADISON, INDIANA.

OIL BURNER.

Application filed October 20, 1927. Serial No. 227,581.

This invention has reference to a liquid fuel burner especially designed for heating purposes, the primary object of the invention being to provide a burner simulating a 5 radiator which may be positioned in a room for heating, the burner being of the wickless type.

An important object of the invention is to provide a burner including a plurality 10 of horizontally disposed bars formed with longitudinal grooves defining lateral flanges, the flanges being formed with openings defining irregular passageways transversely of the bars, to insure the heating of the air to 15 vaporize the oil and produce a flame simulating a gas flame.

Another object of the invention is the provision of means for regulating the blaze so that the device may be efficiently employed 20 in connection with a thermostat control device or may be manually operated to regulate the temperature in a room.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawings:

Figure 1 is a rear elevational view of a 35 heater constructed in accordance with the invention.

Figure 2 is a vertical sectional view through the burner, the radiator section having been removed.

Figure 3 is a fragmental side elevational view of one of the bars forming the burner block.

Figure 4 is a bottom plan view thereof.

Figure 5 is a plan view of the burner, the radiator section having been removed.

Figure 6 is a sectional view taken on line 45 6-6 of Figure 5.

Figure 7 is a fragmental sectional view illustrating the liquid feeding tank.

Figure 8 is an end elevational view of the burner.

Figure 9 is a fragmentary plan view of the fuel trough.

Referring to the drawings in detail, the

base of the burner is indicated generally by 55 the reference character 5 and includes supporting legs 6.

The burner proper includes spaced side plates or casing sections indicated at 7, each of which is provided with an upper inwardly extended flange 8 and a lower outwardly extended flange 9, the flanges 9 of the casing sections being formed with openings to receive securing screws 10 that secure the casing section to the base. 60

The flanges 8 are also provided with bolt 65 openings to receive the bolts 11 that are disposed in spaced relation throughout the lengths of the flanges 8. These bolts 11 also pass through openings formed in the bars 12 to secure the bars together, the bars 12 being of lengths equal to the length of the burner casing proper, and as shown, are provided with grooves 13 formed longitudinally thereof and disposed in the lower surfaces. 70

Openings 14 are formed in the flanges defined by the grooves, which openings of one flange are arranged in staggered relation with the openings of the adjacent flange 80 so that air passing through the burner will take a zig-zag course to insure the heating of the air to vaporize the liquid fuel.

The burner casing is wider than the combined widths of the tiers of bars which are 85 arranged one upon another as clearly shown by Figure 6 so that air passageways 14' are provided between the outer surfaces of the bars and the casing sections, with the result that air may pass upwardly into these 90 passageways where it will pass inwardly to the central portion of the burner.

The bars 12 of the respective tiers are disposed in spaced relation defining a passageway 15 for the flame of the burner. 95 Supported under the tiers of bars 12 is an elongated fuel trough 16 formed with a flange 17 through which the bolts 11 pass to secure the fuel trough in position under the tiers of bars 12. 100

At a point intermediate the ends of the trough 16 is a transversely disposed slot or orifice 18 through which fuel passes as it enters the fuel trough, the slot being substantially small so that only a small quantity 105 of fuel will pass therethrough.

Secured directly under the slot or orifice 18 is a fuel chamber 19 that communicates

with the trough through the orifice 18 so that liquid fuel may pass from the fuel chamber to the trough.

Communicating with the fuel chamber is 5 a pipe 20 which has a lateral extension 21 to which the pipe 22 is connected as by means of the movable union 23, the pipe 22 also being connected with the pipe 24 through the elbow 25, the latter pipe being in communication with the fountain chamber 26 through the pipe 27 and elbow 28. Thus it will be seen that due to this construction, the fountain chamber 26 may be moved vertically to change the level of liquid therein and 15 thereby control the passage of fuel from the fuel chamber 19, and consequently regulate the flow of fuel to the fuel trough 16.

A supply tank indicated at 29 and which is in the form of a bottle is inverted and positioned in the fountain chamber 26 so that when the liquid level in the fountain chamber falls below the mouth of the bottle 29, air will pass into the bottle and allow fuel to 20 pass from the bottle to replenish the fuel 25 in the fuel chamber.

This movement of the fuel chamber controls the size of the flame and consequently the heating capacity of the burner proper, as it will be seen that should the fountain chamber be lowered so that the level of the liquid fuel therein stands below the level of the fuel in the fuel chamber 19, the liquid fuel will cease to flow into the fuel trough, but when the fountain chamber is elevated, to a 30 point to bring the liquid level therein above the liquid level in the fuel chamber, liquid fuel will flow into the fuel chamber and overflow into the fuel trough 16.

Thus it will be obvious that by regulating 40 the fountain chamber, the quantity of fuel consumed may be regulated so that a large or small flame will be produced, it being obvious that by this arrangement of parts, a pilot flame may be provided.

45 The reference character 30 indicates the control rod that is supplied with a handle 31 at its forward end to facilitate the operation thereof, the inner end of the control rod being formed at right angles where it is connected with the link 32 which in turn connects with the fountain chamber 26.

A coiled spring 33 is mounted on the control rod 30 and acts to normally hold the control rod in a position against movement.

55 The radiator coils or heat radiating portion of the heater are indicated at 34, to the end that heat passing upwardly through the

burner will be passed through the radiator coils or tubes to throw off heat into the room.

A pipe indicated at 35 acts to carry off 60 fumes which may be present, due to the burning of the oil, and in connection with this pipe it might be stated that it is contemplated to connect this pipe with pipes or flues leading to the open air.

The operation of the device is as follows:

Oil enters the trough 16 through the slot or orifice 18 where it is burned, the heat from the blaze heating the bars 12 to the end that as air is drawn through the air passageways, 70 the air which has become heated, vaporizes the liquid fuel causing it to burn rapidly in a blue flame.

While I have shown and described a 75 burner of the wickless type especially designed for heating purposes, it is to be understood that a burner of this character may be constructed circular in formation to adapt it for cooking purposes.

I claim:

1. A liquid fuel burner including a base, a fuel trough supported on the base and having flanges, said fuel trough having a slot to admit fuel to the trough, a burner block including spaced tiers, the space between the tiers constituting a vertical passageway, said tiers being mounted on the flanges, each tier embodying a plurality of superposed bars, each bar having a groove formed longitudinally thereof providing parallel flanges having notches formed therein, said notches constituting passageways communicating with the vertical passageway, and a casing forming a part of the burner block and spaced from the bars providing lateral passageways communicating with the vertical passageway through the notches.

2. A liquid fuel burner including a base, a fuel trough supported on the base, a burner block including spaced tiers spaced apart to provide a vertical passageway, said tiers including bars having grooves formed in their under surfaces providing longitudinal flanges, the longitudinal flanges having notches arranged in staggered relation with respect to each other forming irregular passageways, a casing spaced from the tiers, the space communicating with the vertical passageway through the irregular passageways, and means for supplying fuel to the fuel trough.

In testimony that I claim the foregoing as my own, I have hereto affixed my signature.

ARBA IRA CARNINE.
